UNITED STATES PATENT OFFICE.

EARL H. STAUDINGER, OF WAHOO, NEBRASKA.

CHAIN-LOCK.

1,258,373.

Specification of Letters Patent. Patented Mar. 5, 1918.

Application filed September 28, 1917. Serial No. 193,841.

To all whom it may concern:

Be it known that I, EARL H. STAUDINGER, a citizen of the United States, residing at Wahoo, in the county of Saunders and State 5 of Nebraska, have invented certain new and useful Improvements in Chain-Locks, of which the following is a specification.

This invention relates to a chain locking device, for use more particularly in connection with the non-skid chains of automobile tires, and has for its object to provide such 10 a construction that, when applied, it will not become detached or unlocked from vibration of the chains, to be convenient in use 15 and to consist of few and simple parts so that manufacture will be economical.

The invention consists of the novel construction, combination and arrangement of parts as described herein and claimed and 20 as illustrated in the accompanying drawing, wherein,—

Figure 1 is a side view of the device. Fig. 2 is a plan view of the same. Fig. 3 is a sectional view on line 3—3 of Fig. 2. Fig. 4 25 is a side view in section showing the parts in unlocked relation. Fig. 5 is an end view of the housing. Fig. 6 is a side view of the locking-bar. Fig. 7 is a side view of the housing.

Referring now to the drawing for a more 30 particular description, the device is illustrated in connection with a pair of chain links indicated respectively at 8 and 9.

At 10 is indicated a movable locking bar. 35 I provide a housing for the locking bar consisting of a pair of substantially parallel elongated wings α these preferably being connected, as indicated at a at one of their longitudinal edges for a part of their length, 40 and also disconnected for a part of their length to provide a slot b opening on one of their ends.

The housing is provided between its ends and intermediate the wings with a support 45 or block 11 provided with an aperture 12, and preferably it is secured to the wings by a rivet 13, said block being provided with a projection or catch 14 having a convexed part c , said projection being disposed adjacent to that end of the housing opposite to the slot b .

Each wing is also provided with a recess 15 opening on its end above the slot b , and the wings are connected between the slot b and said recesses with a pivot-pin 16. 55

The locking bar 10 is provided at its respective ends with transversely disposed arms 17 and 18, said arm 17 having a slot 19 formed substantially at right angles and also being provided to open on its inner 60 side between said slot and the body of the locking bar with a recess 20.

The arm 18 is provided with an inwardly extending hook-member or projection 21 having a convexed part d . The pivot-pin 65 16 traverses the slot 19, and provides a mounting upon which the locking bar may have swinging movements, and when the parts are disposed in locked relation they will appear as shown in Figs. 1, 2, and 3, 70 the locking bar being housed between the wings α , since the block 11 is disposed inwardly of the free edges of said wings to provide an angular channel or containing-space for that purpose. 75

The chain-link 8 is secured to the block 11 by any suitable means, the means herein shown for this purpose being a bolt 22, said bolt being loosely seated in the aperture 12 and in apertures 23 of the wings, the chain-link being suitably secured to said bolt. Numerals 24 indicate recesses or depressions formed in the outer edge of the locking-bar for convenience of access to the milled edge 25 by an operator when manually sliding 85 said bar longitudinally of the wings for disengaging its projection 21 from the projection 14, the flat contact surface e of the projection 21, by said operation, moving out of engagement with the flat surface e of the 90 projection 14.

When connecting two ends of a chain or connecting one chain with the link of another chain, the bar 10 is moved outwardly, the slot b permitting it to have a free outward swinging movement. The chain link 9 is then mounted upon the bar 10, and by swinging said bar in a reverse direction it will become locked upon the block 11, the flat surface e of its projection 21 being in 100 engagement with the flat surface e of the projection 14, the chain-link 9 being con-

fined within recesses 15 and 20. During this movement the convexed surface *c* will slide on the convexed surface *d* which greatly facilitates operation.

5 Among some of the advantages to be derived by use of the invention, it may be stated that the parts are so arranged that the device, while fully operative for all purposes of a chain-lock may have a less 10 length and width than usual, and therefore will not be obtrusive when used upon a wheel tire. It will be noted that no stresses of importance are directed at any time to the pivot-pin 16. Also that the stresses are 15 sustained by the bar 10 and block 11, and that so far as the stresses sustained by the bar are concerned, they are for the most part directed longitudinally of said bar.

It will be seen that the chain-lock thus 20 described may be unlocked only after the chain-link 9 has been moved inwardly within the recess 15 a sufficient distance to permit such a required longitudinal movement for the bar 10 as will be necessary for the 25 release of its projection 21 from the projection 14, and therefore the construction provides such proportions for the recesses 15 and 20 that the chain-link 9 may have this movement; and since this is not a normal 30 movement for the link 9, the parts will normally remain in locked relation until an operator manually moves the locking bar 10 for unlocking the device.

While the utility of the invention has been 35 described in connection with conventional non-skid tire chains, it is obvious that it may be used for other purposes.

What I claim as my invention and desire to secure by Letters Patent is,—

40 1. In a locking device for chain links, a pair of substantially parallel wings connected at one of their longitudinal edges, said wings being provided with a pivot-pin and having recesses opening on one of their 45 ends for receiving a chain-link, a supporting-block between and having a projection disposed adjacent to that end of the wings opposite to the recesses, a locking-bar provided at one of its ends with a transversely disposed arm having a recess opening on its inner side and also provided with a slot for receiving said pivot-pin, said locking-bar being provided at its opposite end with a second transversely disposed arm having an 50 inwardly extending projection, said bar being adapted to have a swinging movement for locking said chain-link within the recesses of the wings and the recess of said first named arm and to move its projection 55 into locked relation with the projection of said block, and a member traversing the wings and said block for a mounting of a second chain-link.

60 2. In a locking device for chain-links, a

pair of apertured, parallel, connected wings 65 provided with a catch-member, a bolt in said apertures to provide a mounting for one chain-link, a locking-bar provided at one of its ends with a projection and connected at its opposite end with the wings, 70 said locking-bar being adapted to be disposed within a second chain-link and to have a swinging movement to be disposed in the plane of said wings, its projection moving into engagement with the catch-member of 75 said wings.

3. In a locking device for chain links, a pair of connected, substantially parallel wings provided with a pivot-pin and having recesses opening on one of their ends for receiving a chain-link means for pivotally mounting a second chain link on said wings, a supporting-block between and having a projection with a convexed part disposed adjacent to that end of the wings opposite to 85 said recesses, a locking-bar provided at one of its ends with a transversely disposed arm having a recess opening on its inner side and having a slot for receiving said pivot-pin, said locking-bar being provided at its 90 opposite end with a second transversely disposed arm provided with an inwardly extending projection having a convexed part, said locking-bar being adapted to have a swinging movement for engaging the convexed part of its projection with the convexed part of said block and to have longitudinal movements to dispose its projection in locked relation with the projection of 95 said block for maintaining the first named 100 chain-link within the recesses of the wings and said first named arm.

4. In a locking device for chain-links, a pair of apertured, parallel, connected wings having a catch-member therebetween, said 105 catch-member being provided with a convexed part, means engaging in said apertures for supporting a chain-link, a locking-bar provided at one of its ends with a projection having a convexed part, its opposite end being connected with said wings, 110 said locking bar providing a mounting for a second chain-link and adapted to have a swinging movement to dispose the convexed part of its projection in engagement with the convexed part of said catch-member and to have longitudinal movements for being disposed in locked relation with said catch-member.

5. In a locking-device for chain-links, a 120 pair of connected, adjacent wings, a block provided with a projection and disposed between the wings, a locking-bar having a transversely disposed arm between and pivotally connected with said wings and having 125 a second transversely disposed arm provided with a projection, said locking-bar being adapted to having a swinging movement for

confining a chain-link between the wings and said first-named transverse arm, its projection moving into locked relation with the projection of said block, and means for connecting a chain-link to the wings and said block.

In testimony whereof, I have affixed my signature in presence of two witnesses.

EARL H. STAUDINGER.
